(57) **CLAIM**

The ornamental design for a combined razor cartridge and connector, as shown and described.

DESCRIPTION

FIG. 1 is a front, top, perspective view of a combined razor cartridge and connector showing my new design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof; and,

FIG. 8 is a rear perspective view thereof.

The broken lines shown in the drawings illustrate portions of the combined razor cartridge and connector and form no part of the claimed design.
